U.S. Appl. No. 29/613,318 to Hiroyuki Sunagawa, which was filed on Aug. 9, 2017.

Primary Examiner — Jeffrey D Asch*Assistant Examiner* — Rebekah A Caruso(74) *Attorney, Agent, or Firm* — Greenblum & Bernstein, P.L.C.(57) **CLAIM**

I claim the ornamental design for a wireless communication tag, as shown and described.

DESCRIPTION

FIG. 1 is a front view of a wireless communication tag, showing my new design;

FIG. 2 is a rear view thereof;

FIG. 3 is a left side view thereof;

FIG. 4 is a right side view thereof;

FIG. 5 is a top plan view thereof; and,

FIG. 6 is a bottom plan view thereof.
